UNITED STATES PATENT OFFICE.

WILLIAM H. EBELHARE AND CLARENCE G. ARVIDSON, OF INDIANAPOLIS, INDIANA,
ASSIGNORS TO THE STENOTYPE COMPANY, OF INDIANAPOLIS, INDIANA.

STENOGRAPHIC TYPE-WRITING MACHINE.

1,264,909.

Specification of Letters Patent. Patented May 7, 1918.

Application filed October 12, 1916. Serial No. 125,224.

To all whom it may concern:

Be it known that we, WILLIAM H. EBELHARE and CLARENCE G. ARVIDSON, citizens of the United States, and residents of Indianapolis, in the county of Marion and State of Indiana, have invented certain new and useful Improvements in Stenographic Type-Writing Machines; and we do hereby declare the following to be a full, clear, and 10 exact description of the invention, such as will enable others skilled in the art to which it appertains to make and use the same.

This invention relates to improvements in typewriting machines and more particularly 15 to such as are adapted for use in writing shorthand.

One object of the invention is to provide a stenographic typewriting machine in which the operating mechanism shall be simply and 20 compactly supported in a comparatively small framework, and thus minimize the size and weight of the machine.

A further object is to provide a stenographic typewriting machine in which the 25 inking ribbon and paper feeding mechanisms shall be controlled from respective ends of a universal bar.

With these and other objects in view, the 30 invention consists in certain novel features of construction and combinations of parts as hereinafter set forth and pointed out in the claims.

In the accompanying drawings; Figure 1 is an elevation showing one side of a stenographic typewriting machine; Fig. 2 is an elevation of the opposite side of the machine; Fig. 3 is a face view of the blank of the universal bar; Fig. 4 is an elevation at one end of the universal bar; Fig. 5 is an elevation at the other end of the universal bar; Fig. 6 is a plan view; Fig. 7 is a side view of the universal bar, and Fig. 8 is a longitudinal sectional view of the machine.

1 represents the frame of the machine in 45 which the key and type mechanisms are mounted, but as these mechanisms are not claimed specifically herein, a detail description of the same is not essential to an understanding of the features of invention contemplated by the appended claims.

A platen cylinder 2 is mounted in the rear portion of the frame and serves as a part of the paper feed mechanism,—suitable feed rollers 3 and paper guiding devices 4 being also mounted in the rear portion of

the frame so as to be coöperable with the platen cylinder to feed the paper when said cylinder is turned. The front end of the frame accommodates the keyboard 4^a, and the key levers 5 (which are pivotally mounted at 6), coöperate with bell-crank 7,—the upper arms of the latter being pivotally connected with horizontally disposed type bars 8 so as to move the latter toward and away from the platen cylinder when the 65 keys are actuated.

An inking ribbon passes from one reel 9 to another and between the type faces and the platen cylinder. These reels are driven in one direction or the other by means of 70 gearing 10, the latter being actuated, by a shaft 11 mounted horizontally in the framework and motion is imparted to this shaft each time a key lever is depressed, by means of devices which will be hereinafter de- 75 scribed.

A universal bar 12 is disposed transversely in the lower portion of the framework somewhat in advance of the pivotal mountings of the key levers and under the latter so 80 as to be actuated thereby. The universal bar 12 is shown in detail in Figs. 3 to 7 of the drawings and may be conveniently made in a single piece of sheet metal (preferably steel). The sheet metal blank shown in Fig. 85 3 comprises a body portion 13 provided at respective ends with necks 14—15. From the outer end of the neck 14, an arm 16 projects at an obtuse angle therefrom and is formed at its free end with a rounded head 90 17, while said arm is provided centrally between its ends with a hole 18. From the outer end of the neck 15 at the other end of the body 13 an arm 19 projects at an obtuse angle and is formed near its respective ends with fingers 20 and 21. Near the juncture of the finger 20 with the arm 19, a hole 22 is provided in the latter. The side portions of the body 13 of the universal bar blank are bent upwardly to form parallel 95 flanges 23 to engage the side edges of a cushion 24 located on said bar in position to be engaged by enlargements on the lower edges of the key levers. The outer portion of the neck 14 is bent upwardly at right 100 angles so that the arm will be caused to project upwardly and rearwardly, as shown in Figs. 1 and 4, and the neck 15 at the other end of the bar is similarly bent so that the arm 19 will project upwardly and rear- 115

wardly. Suitable pivotal studs carried by the machine frame, enter the holes 18 and 22 of the arms 16 and 19,—said studs being so located that the pivotal supports thus formed shall be in line with the pivotal mountings of the key levers.

The universal bar 13 is maintained in and returned to its normal position under the key levers by means of a spring 25 attached 10 at one end to the frame and at the other end to the finger 20 at the end of the universal bar arm 19 as shown in Fig. 2.

A bell-crank lever 26 is pivotally mounted at 27 in the framework and the free end 15 of the arm 28 of this lever is bifurcated to receive the headed rear end of arm 16 of the universal bar, as shown in Fig. 2. The upwardly projecting arm 29 of the bell-crank is connected, by means of an L-shaped 20 link 30 with an oscillatory plate or pawl carrier 31 mounted loosely at one end of the platen cylinder. A spring-actuated pawl 32 is pivotally attached to the plate or carrier 31 and engages a ratchet wheel 33 25 having fine teeth, rigidly connected with the platen cylinder. It is apparent that when a key lever is depressed, the universal bar will be also depressed and motion will be imparted through the medium of the bell-crank 20 and link 30 to the plate or carrier 31 and the pawl 32, engaging the fine-toothed ratchet wheel 33, will impart motion 30 to the platen cylinder and thus cause the paper to be fed a distance sufficient for 35 line spacing.

At the side of the machine opposite that at which the paper feed mechanism above described is located, a ratchet wheel 34 is secured to the shaft 11 of the ribbon feed 40 gearing. A plate or carrier 35 is loosely mounted adjacent to this ratchet wheel and carries a spring-actuated pawl 36 to engage said ratchet wheel 34. This plate is provided in its lower portion with an elongated 45 slot 37 to receive a pin 38 projecting laterally from the finger 21 of the arm 19 of the universal bar,—the connection between the pawl carrier 35 and the universal bar being thus located in front of the pivotal mountings 50 of both the universal bar and the key levers. Thus when a key lever is depressed, the downward movement of the universal bar will cause the plate or carrier 35 to move downwardly and the pawl 36 to ride freely 55 over the teeth of the ratchet wheel 34 on the ribbon feed gear shaft. When the key lever is released and permitted to rise, the spring 25 will cause the universal bar to rise with it, and the connection between the 60 arm 19 of the universal bar and the plate or carrier 35 will cause the latter to be raised and the pawl 36 to propel the ratchet wheel 34, thus turning the ribbon feed gearing and feeding the ribbon a short distance. It will 65 thus be observed that the inking ribbon is

fed on the return stroke of a key lever and after the type has printed upon the paper and a new surface of ribbon will be presented ready for the next impression.

With the construction and arrangement of parts above described, the paper feed mechanism is operated from one end of the universal bar during the depression stroke of a key bar and the ribbon feed mechanism is operated from the other end of the universal bar, during the return stroke of a key lever. By such construction, I am enabled to build both feed mechanisms and their operating means in a compact structure which is simple and readily accessible as well as accurate in operation and not liable to get out of order.

Slight changes might be made in the details of construction of our invention without departing from the spirit thereof or 85 limiting its scope, and hence we do not wish to restrict ourselves to the precise details herein set forth.

Having fully described our invention what we claim as new and desire to secure 90 by Letters-Patent, is:—

1. In a typewriting machine, the combination with key levers, ribbon mechanism and paper feed mechanism, of a universal bar disposed under the key levers, said bar having upwardly projecting arms at its respective ends, means pivotally supporting said arms to pivotally support the universal bar under the key levers, operating connections between the free end of the arm at one end 100 of the universal bar and the ribbon mechanism, and operating connections between the free end of the arm at the other end of said bar and the paper feeding mechanism.

2. In a typewriting machine, the combination with key levers, paper feed mechanism, and ribbon feed mechanism, of a universal bar provided at its respective ends with arms fixed thereto, means pivotally supporting said arms, ratchet devices for operating the paper feed mechanism, operating connections between said ratchet devices and the arm at one end of the universal bar, ratchet devices for operating the ribbon mechanism, and operating connections between said last-mentioned ratchet devices and the arm at the other end of said universal bar.

3. In a typewriting machine, the combination with pivotally-mounted key levers, ribbon mechanism and paper feed mechanism, of a universal bar disposed under the key levers, said bar provided at its respective ends with upwardly projecting arms, means pivotally supporting said arms, operating means for the paper feed mechanism connected with the free end of one of said arms in rear of the pivotal mounting of the key levers, and operating means for the ribbon mechanism connected with the free end of the other arm of the universal bar at a point 125 130

in front of the pivotal mounting of the key levers.

4. In a typewriting machine, the combination with key bars, paper feed mechanism and ribbon mechanism, of a universal bar coöperable with the key bars and said mechanisms, said universal bar comprising a sheet metal body portion having upturned flanges at its edges, integral arms at respective ends of said body portion, said arms projecting upwardly and rearwardly, means pivotally supporting said arms, and operat-

ing connections between the arms of the universal bar and the ribbon and paper feed mechanism respectively.

In testimony whereof, we have signed this specification in the presence of two subscribing witnesses.

WILLIAM H. EBELHARE.
CLARENCE G. ARVIDSON.
